UNITED STATES PATENT OFFICE.

ALBERT ABRAMS, OF PARIS, FRANCE.

GARMENT-CREASING DEVICE.

No. 874,818.

Specification of Letters Patent.

Patented Dec. 24, 1907.

Application filed March 21, 1907. Serial No. 363,675.

To all whom it may concern:

Be it known that I, ALBERT ABRAMS, a citizen of the United States of America, residing at Paris, France, have invented new and useful Improvements in Garment-Creasing Devices, of which the following is a specification.

This invention relates to wearing apparel, and it relates more particularly to means whereby garments for men or women may be permanently creased.

The invention has for one of its objects to provide an attachment for garments which retains the initial crease imparted to the material and at the same time, permits of ample flexibility of the fabric under strain so that it will not be visible that the garment is fitted with the crease-retaining means.

A further object of the invention is the provision of a crease-retaining means which is of comparatively simple and inexpensive construction and so designed that it can be put up for the market in strip or tape form and be ready to apply to the garment in a simple and easy manner.

With these objects in view and others, as will appear as the description proceeds, the invention comprises the various novel features of construction and arrangement of parts as will be more fully described herein-after and set forth with particularity in the claims appended hereto.

In the accompanying drawing, which illustrates one of the embodiments of the invention, Figure 1 is a perspective view of a pair of trousers equipped with the crease-retaining device. Fig. 2 is a fragmentary sectional view through one of the legs of the trousers and showing the crease-retaining means applied. Fig. 3 is a fragmentary perspective view of the garment drawn on an enlarged scale.

Similar reference characters are employed to designate similar parts throughout the several figures.

In the present instance, I have elected to illustrate the crease-retaining means as applied to a pair of trousers, but it is to be understood that it can be used in connection with coats or dresses for women or other garments where creases are desired to be permanently maintained.

Referring to the drawing, the crease-

retaining device comprises a pair of strips or tapes of elastic webbing 1 that are adapted to extend the full-length of the crease to be preserved. These strips of webbing are arranged parallel and with their edges in close proximity, and secured to the strips and extending the full length thereof is a piece of thin rubber 2, whereby a hinged connection is formed between the two pieces of webbing 1. The rubber piece 2 is preferably secured to the webbing by rubber cement, although any other waterproof adhesive may be used. The strips are further united at suitable intervals by short pieces of elastic cord 3 having their ends secured to the webbing in any suitable manner. On the outer surfaces of the strips of webbing 1 are applied pieces of gutta percha sheeting 4 such as is commonly used by tailors for repairing purposes. The crease-retaining attachment is put up for market in this form and all that is required to attach it to a garment is to place it on the under side of the fabric where the crease is desired and then pass a hot iron over it so that the gutta percha sheeting will be softened and stuck to the fabric. It will thus be seen that no sewing or stitching is required and that a comparatively light attachment is produced that maintains a comparatively decided crease. Since the elastic strips of webbing 1 that in fact constitute the body of the attachment, are elastically connected at their meeting edges, the garment is free to bend as at the elbow, knee or any other part stretched over a member of the body and the fabric of the garment is stretched without the attachment being visible, and as soon as the pressure is removed from the fabric, the attachment re-adjusts itself and preserves the crease.

By reference to Fig. 1, the crease-retaining device or attachment is applied to the legs of the trousers on the inner surface thereof and in line with the creases 6. The crease-retaining devices are indicated by dotted lines at 7 and extend from the lower ends of the legs upwardly to any desired point.

I have described the principle of operation of the invention, together with the device which I now consider to be the best embodiment thereof, but I desire to have it understood that the device shown is merely illus-

trative and that such changes may be made when desired as are within the scope of the claims.

Having thus described the invention, what

5 I claim is:—

1. As an article of manufacture, a crease-retaining device comprising a pair of separate strips of elastic webbing, a strip of rubber secured to the strips at their meeting 10 edges to hingedly connect the strips together, and adhesive material on the outer surfaces of the webbing strips whereby the device can be secured to a garment by applying heat to the strips.
- 15 2. As an article of manufacture, a crease-retaining device comprising a pair of strips arranged with their edges in proximity, a strip of elastic material glued or cemented to the strips for hingedly connecting them,

and strips of gutta percha sheeting applied 20 to the outside of the strips, and elastic cords connecting the meeting edges of the strips together.

3. As an article of manufacture, a crease-retaining means comprising strips of elastic 25 material arranged with their edges in proximity, a strip of rubber cemented to the inner surfaces of said strips to hingedly connect them, and pieces of gutta percha sheeting applied to the outside of the first-mentioned 30 strips.

In testimony whereof, I affix my signature in presence of two witnesses.

ALBERT ABRAMS.
